(57) **CLAIM**

The ornamental design for a speaker and microphone housing, as shown and described.

DESCRIPTION

FIG. 1 is a perspective view of a speaker and microphone housing that is a first embodiment of the invention, showing a microphone assembly (in phantom) mounted thereon; FIG. 2 is a top plan view of the speaker and microphone housing of FIG. 1;

FIG. 3 is a bottom plan view of the speaker and microphone housing of FIG. 1;

FIG. 4 is a front elevational view of the speaker and microphone housing of FIG. 1;

FIG. 5 is a back elevational view of the speaker and microphone housing of FIG. 1;

FIG. 6 is a right side elevational view of the speaker and microphone housing of FIG. 1;

FIG. 7 is a left side elevational view of the speaker and microphone housing of FIG. 1;

FIG. 8 is a perspective view of a speaker and microphone housing that is a second embodiment of the invention, showing a microphone assembly (in phantom) mounted thereon;

FIG. 9 is a top plan view of the speaker and microphone housing of FIG. 8;

FIG. 10 is a bottom plan view of the speaker and microphone housing of FIG. 8;

FIG. 11 is a front elevational view of the speaker and microphone housing of FIG. 8;

FIG. 12 is a back elevational view of the speaker and microphone housing of FIG. 8;

FIG. 13 is a right side elevational view of the speaker and microphone housing of FIG. 8; and,

FIG. 14 is a left side elevational view of the speaker and microphone housing of FIG. 8.

The broken lines depict environment that forms no part of the claimed design.
